SURGICAL CAST-SUPPORTED FINGER EXERCISER

Joseph A. De Mona, Warren Point, N.J.

Application August 15, 1942, Serial No. 454,980

1 Claim. (Cl. 128—26)

This invention relates to kinesitherapy and more particularly to exercisers for the hands and fingers.

In injuries to the hand and arm, it is frequently necessary to place the arm, or a portion thereof, or a portion of the hand as well, in a cast or other surgical device for supporting the injured parts. After a period, with the injured parts so supported, the fingers, associated with such injured parts, become increasingly stiffened, as is well known in surgery, if the fingers are not frequently and properly manipulated. Physicians and surgeons may manually manipulate their patients' fingers or instruct them how to attend to this themselves, but patients are apt to grow careless as to proper manual manipulation, after a time, or to neglect it, as a task, devoid of novelty. In industry and the military service, where large numbers of persons may suffer arm or hand injuries, there may not be enough physicians, surgeons and nurses to provide regular, proper manipulation of the fingers after casts have been applied, and this duty falls to the patients themselves.

An important object of this invention is to provide a novel device, adapted to be associated with a cast or the like, which device may be readily detachably secured to the fingers and operated by the uninjured hand of the patient, or by another person, so as to properly manipulate the fingers in order to keep them supple, restore circulation and aid in healing the injured parts.

Another important object is to provide such a device, the supports of which may be rigidly anchored in the cast and, when the cast is removed and broken up, the device may be again employed, associated with a new cast.

Still another important object is to provide a manipulator, as described, so compact in structure and so secured to the body of the patient that it is not in the way, to any degree, and is always in position to be operated. This in contradistinction to devices which may be employed to exercise the fingers and have no means for securing them to the person, or are provided with wrist straps and removed after exercising. One of the novel features of this device is that the patient has the device with him and attached to his person at all times, so that it is a reminder and so that, if he is not able to go for and attach a device of this kind, it is available instantly for use.

Yet another important object is to provide an inexpensive and readily manufactured device of this kind, which may be turned out quickly and in large quantities and, being particularly compact, takes up but little room for shipment and storage.

Another object is to provide a device, as described, which is adapted to support the forearm, with the fingers free.

Still another object is to provide such a device, portions or accessories of which may be supplied from any physician's or surgeon's or first-aid kit. This applies to means for detachably securing the device to the fingers—the only portion of the device actually coming into contact with the patient's person. This means, of course, may be discarded from time to time.

Other objects and advantages of this invention will be apparent during the course of the description of this invention, taken in connection with the accompanying drawing, forming a portion of this specification, and in which drawing:

Fig. 1 is a perspective view of the novel exerciser illustrating it secured to a surgical cast, parts being broken away to better show portions of the construction.

Fig. 2 is a top plan view of a portion of the support and operating means of the novel exerciser.

Fig. 3 is an end elevation of the same.

Fig. 4 is a clip forming a portion of the operating means.

In the accompanying drawing, wherein for the purpose of illustration is shown only a preferred embodiment of the invention and wherein similar reference characters designate corresponding parts throughout the several views, the letter A may designate a surgical cast; B, the fingers and a thumb of a human hand; C, the novel exerciser as a whole; D, support means; E, anchoring means; F, operating means; G, connection or link between the operating means F and a finger grip means H.

The surgical cast A, shown by way of example, is one placed about the palm portion and back of the hand, but the cast may of course embrace the forearm as well, or extend to the shoulder and in the claims where the expression "surgical arm cast" is employed, the word arm is intended to embrace the upper arm, forearm, wrist and palm portion of the hand. It includes a hardened plastic 10 which is generally applied, in a plastic state, between wrappings of a suitable nature, as is well known in the art. In the example shown substantially all the fingers and thumb portions 15 and 16 respectively, of the hand B, extend from the cast A, with the finger tips shown at 17.

Now, as for the novel exerciser C, this is shown, by way of example, constructed of wire, pull chain and conventional adhesive tape.

The support means D may include a length of suitable rigid wire formed into a pair of substantially paralleling arm portions 20 of appreciable length, sufficient enough to enable the finger tips 17 to clear any surface upon which the support rests, as the fingers 15 move in response to the operations of the exerciser. The arm portions 20, at their lower ends 21, are connected by a base portion 22 having a generally

straight length, and forming, with either arm portion 20, substantially a right angle. Intermediate the lower ends 21 and upper ends 23 of the arm portions 20 are disposed suitable bearings 24, which may be welded, soldered or otherwise suitably secured to the arm portions 20, with their openings in substantial alignment.

Extending from the upper ends 23 of the arm portions 20 is the anchoring means E. This may comprise a portion of the length of wire referred to, forming a pair of substantially straight projections 25 from the arm portions 20 (really being a continuation of the arm portions) and a pair of preferably undulating or corrugated projections 26 extending somewhat perpendicularly with reference to the projections 25, as shown in Fig. 1, where these projections 26 extend away from the fingers 15. A relatively long pair of undulating projections 26 are provided not only to provide substantial anchorage but also because the arm and the cast may be supported, raised from a supporting surface by the support means D. The projections 26 also strengthen the cast A.

The operating means F is shown as a length of wire formed into a handle portion 30, and a bell crank portion 31, with the wire extending through the bearings 24 and the bell crank portion 31 extending between the arm portions 20. Preferably four throws 32 are provided for the bell crank portion 31, with a clip receiving section 33 to each throw. From Figs. 2 and 3 it may be seen how the throws 32 may be arranged. This has been found to be the best arrangement for a finger exerciser for an injured arm or hand. Pivotedly carried by each throw 32 at the clip receiving section 33 thereof is a suitable clip or connector 34, which may be formed of springy wire, and include a pair of arms 35, diverging from a pull chain receiving eye 36 with the wire not quite touching as at 37, in forming the eye. The free ends of the arms 35 are formed into a pair of eyes 38 embracing the clip receiving section 33 in a pivotal connection therewith. A suitable knob 39 may be provided for the handle portion 30. From Fig. 2 it may be seen that there are no sharp bends in the construction shown.

As for the connection or link G between the operating means F and finger grip means H, it is preferred to provide lengths of conventional pull chain 40. This chain, which is frequently employed, associated with electric light sockets, has no sharp edges nor projections. Four such lengths are provided with one of the end portions of each accommodated in a pull chain receiving eye 36, for the eye 36 is a little less in inner circumference than is the circumference of the spheres or beads 41 of the pull chain 40. And the space provided at 37 in the clips 34 will accommodate the short length of connecting material 42 between each sphere 41. Thus, when the pull chain is slipped through the space at 37, one of the spheres 41 will be caught and retained by the eye 36, and it is now apparent that many adjustments in length of the pull chain 40 is possible. Carried at the opposite end portion of each pull chain 40 is a second clip 45, which may be termed the finger grip means clip. This is shown in detail in Fig. 4 and may be formed, of a length of springy wire, into an eye portion 46, with the wire not quite closing the eye as at 47, a pair of arm portions 48 and an adhesive tape receiving portion 49 at the end of the clip 45 opposite the eye portion 46. The

eye portion 46 with the space 47 function similarly to the eye 36 and space 37 of the clips 34.

The finger grip means H may comprise two short lengths of conventional adhesive tape 50 and 51 for each finger to be exercised. The ends of the length 50 may be secured to the finger tip 17 with the remaining portion of the length 50 forming a loop 52, looped over the adhesive tape receiving portion 49 at the end of the clip 45. Then the second length 51 of the tape may be wrapped about the finger tip, overlapping the ends of the length 50, as shown in Fig. 1. Since adhesive tape is widely used and is inexpensive, after the cast is removed the lengths 50 and 51 of tape may be discarded.

Owing to the employment of the flexible pull chain, and the clips 34 and 45 wide adjustment in the lengths of the pull chains is possible, less than four fingers may be exercised, if desired (by omitting one or more of the chain connections) and if it is desired to free the fingers of the pull chain connections at any time, the connections may be readily slipped from the clips 45. And they may be as readily slipped into the clips 45.

As the surgical cast A is being formed and is still plastic, the anchoring means E is inserted into the cast, with the support means D depending from the cast. The position of the exerciser C along the arm depends upon the position of the cast. From the example shown, it is apparent that the position of the depending support means D may be at substantially the palm portion of the hand. The finger grip means H may now be adjusted and, after the cast has hardened, the pull chains adjusted in the clips 34 and 45, so that, when the arm is supported by the support means D upon the base portion 22 thereof, the knob 39 grasped by the uninjured hand of the patient (the exerciser C may be constructed for use on the left or right hand by suitably placing the handle portion 30, as is apparent) and as the operating means F is rotated, the fingers will be flexed, with the tips drawn so as to form a fist, a cupped hand or so that there will be only a slight movement of the fingers, either outstretched or in any other position they may assume. The adjustments of the connections G may of course be made with the fingers in any position except with the hand closed. Alternately moving the connection G toward and away from the support means D, as the bell crank rotates, will cause the fingers to move therewith and even a slack developing in the pull chain will not dislodge it from the clips.

Various changes may be made to the form of the invention herein shown and described or to the method of applying the exerciser and manipulating it without departing from the spirit of the invention or scope of the claim.

What is claimed is:

In a finger manipulator adapted for association with a surgical arm cast, a rigid support, including a pair of substantially paralleling upwardly extending arm portions, a base portion extending from like lower ends of said arm portions and transversely of said cast and a pair of corrugated anchoring portions extending from and normal to like upper ends of said arm portions and adapted to be imbedded in said cast to lay longitudinally thereof; a bell crank rotatively carried by said arm portions; a finger grip; and a flexible link connecting said bell crank and finger grip.
